DOOR LOCKING MECHANISM

Walter J. Duvall, Chula Vista, Calif.

Application November 15, 1954, Serial No. 468,680

7 Claims. (Cl. 292—165)

This invention relates to a locking door pull for sliding doors.

It is an object of my invention to provide an improved, simple, efficient and economically constructed locking door pull for sliding doors.

It is more particularly an object of my invention to provide such a device which can be set in locked position while the door is open or closed, but which will actually not lock unless and until the door is closed. In this way, it is impossible for the user to close a locked door and damage the locking mechanism.

It is a further object of my invention to provide a device of the class described which is so compact and narrow in width that it will fit within a notch cut in the front edge of the narrowest sliding doors in conventional use at the present time.

Because of the complex mechanical nature of the door locking mechanism of the present invention, further aims and objects of the invention are best more fully explained in conjunction with an explanation of the accompanying drawings illustrating a door locking mechanism constructed in accordance with my invention.

While I have shown in the accompanying drawings a preferred embodiment of my invention, it should be understood that the same is susceptible of modification and change without departing from the spirit of my invention.

Referring to the drawings, Fig. 1 is a front view of a locking door pull of my invention;

Fig. 2 is a cross-sectional view taken on line 2—2 of Fig. 1;

Fig. 3 is a cross-section view taken on line 3—3 of Fig. 1;

Fig. 4 is a cross-sectional view taken on line 4—4 of Fig. 1;

Fig. 5 is a cross-sectional view taken on line 5—5 of Fig. 1;

Fig. 6 is an isometric view of a latch employed with the invention;

Fig. 7 is an isometric view of a latch retainer employed with the invention;

Fig. 8 is a side view of a locking door pull of the invention partially broken away to show certain constructional details.

A preferred embodiment which has been selected to illustrate my invention comprises a locking door pull having a housing 12. A cover 14 having an elongated front opening 16 is adapted to fit over an enlarged front section 18 of housing 12. Housing 12 is provided with a narrower back section 22 formed with an enlarged side opening 24 therein for use in assembling the lock mechanism.

A pull 26 having parallel attaching lugs 28 at its upper end is mounted by means of pivot pins 30 upon the interior of the front section 18 so that the front face of an elongated shank 32 forming part of the pull 26 is normally held by gravity so that it lies flush within the front opening 16 when not in use. A projection 34 is

2

attached to the bottom of the shank 32 so as to normally project into the front section 18 when the door pull 26 is not in use. In use, the door pull 26 may be swung out through the opening 16 by merely pressing on the upper portion of the shank 32 to move the bottom of shank 32 outwardly. The projection 34 can then be grasped to pull a door (not shown) to which the complete locking mechanism is attached by mounting the same in a notch which is cut in the front edge of the door.

As is most clearly seen in Figs. 1 and 2 of the drawings, the pull 26 is spaced from the top of the front opening 16 so as to provide a space through which a hook 36 may be passed in using the complete lock mechanism as shown in Fig. 8 of the drawing. Immediately in back of this opening 16 there is positioned a sliding latch retainer 38 including side projections 40. These side projections 40 are normally held upon shoulders 42 defining a latch retainer slide within the front section 18. This latch retainer 38 is formed having a top wall 44 which slides against a top 46 of the housing 12. The latch retainer 38 is normally urged toward the front opening 16 by means of a spring 48 located between the vertical leg of an L-shaped support 50 secured within the housing 12 and a front wall 52 forming a part of the sliding latch retainer 38. Thus, as is most apparent in Fig. 2 of the drawings, the spring 48 passes through an opening 54 formed within the latch retainer 38. The spring 48 is held in position with respect to the support 50 by means of a small projection 56 which is attached to this support 50 so as to pass into the end of the spring 48 adjacent to the support.

The latch retainer 38 includes a lower projection 58 having a bottom wall 60 which is designed to slide upon the horizontal leg of the support 50. This projection 58 is designed to normally engage a notch 62 formed upon a latch 64 in order to control the movement of this latch 64. The latch 64 is formed of the shape indicated in Fig. 6 of the drawings. From an examination of this figure in conjunction with Figs. 2, 3, 5 and 8 of the drawings, it will be seen that the latch 64 includes elongated sides 66 which are designed to slide upon shoulders 68 formed within the front section 18 from an open position as indicated in Fig. 3 of the drawings to a closed position as indicated in Fig. 8 of the drawings.

The latch 64 is normally urged toward this closed position through the action of a pair of coil springs 70 which are located between the shoulders 68 and the sides of the front section 18 so as to rest against the bottom of this front section 18 and exert upward pressure against a pair of small lugs 72 formed upon the sides 66. The main body 74 of the latch 64 projects back through the front section 18 toward the back section 22 where it is provided with a generally circular socket 76 which is designed to hold a cylindrical ball-shaped segment 78 formed upon the front end of a control arm 80 which projects from the back section 22 into the front section 18.

One end of the control arm 80 is pivotally mounted on 60 a shaft 82. The control arm 80 is provided with a cam surface 90 which cooperates with a cam 92 which is formed on a rotating locking member 94.

A retainer plate 84 is secured to the housing 12 by small pins 86 engaged holes 88 formed in the back section 22 as indicated in Fig. 2 of the drawings. The retainer plate 84 covers the back portion of the locking mechanism and is provided with a centrally disposed circular opening into which fits a circular shoulder 96 formed upon the locking member 94.

The locking member 94 is provided with a centrally disposed square opening 98 which is designed to be engaged by means of a conventional square shaft (not

shown) of the type normally secured to manually operated control means used with a locking mechanism. The locking member 94 is provided with a first flat surface 100 which is designed to bear against another flat surface 102 formed upon a locking retainer 104. The locking retainer 104 is generally U-shaped, and includes sides 106 which are designed to slide vertically between the back of the vertical leg of L-shaped support 50 and another support member 108 secured to the housing 12. It is normally biased toward the locking member 94 by means of a coil spring 110 which is positioned between the locking retainer 104 and a lug 112 secured to the housing 12. The locking member 94 also includes a second flat surface 114 which is designed to fit against the flat surface 102 of the locking retainer 104 when the locking member 94 is turned so as to remove the cam 92 from contact with the cam surface 90 of the control arm 80.

The flat surfaces 114 and 102 act to hold the locking member 94 in a fixed unlocked position. The flat surface 100 cooperates with the flat surface 102 to serve the same function when the locking member 94 is in locked position as shown in Fig. 2. The result is that the lock is held directly in either locked or unlocked position. This may be important when a user merely looks at the lock control to determine whether or not the door is locked.

The edge of the cam 92 engages the corner of the locking retainer 104 to act as a stop to limit the clockwise rotation of the locking member 94. The opposite end of the cam 92 engages the rounded pivotal portion of the control arm 80 adjacent the shaft 82 to act as a stop to limit the counter-clockwise rotation of the locking member 94.

When the locking member 94 is moved out of contact with the control arm 80, the latch 64 is normally urged by the springs 70 so that the notch 62 is fitted against the projection 58 on the latch retainer 38. When the complete locking mechanism is so disposed, it is ready for use in locking. When the door is closed, the hook 36 passes through the front opening 16 and bears against the latch retainer 38, pushing it back from the extended position shown in Fig. 2 to the withdrawn position indicated in Fig. 8. As this occurs, the projection 58 is forced out of contact with the notch 62, enabling the latch 64 to be moved upwardly by the action of the springs 70 to a closed position. When this occurs, the latch 64 engages the hook 36 as indicated in Fig. 8 of the drawings and the hook is locked within the locking mechanism.

To unlock the locking mechanism so that the hook 36 is released, the locking member 94 is rotated by external manual control, forcing the cam 92 against the cam surface 90 of the control arm 80. Through the action of the socket 76 and the ball-shaped segment 78 constituting a ball and socket joint, the latch 64 is moved downwardly to an open position, as shown in Fig. 2. When this occurs the hook 36 is released and when it is removed from the locking mechanism, the latch retainer 38 is moved by virtue of the action of the spring 48 so that the projection 58 fits again within the notch 62.

Those skilled in the art will realize from the foregoing description that the mechanism herein described is comparatively simple to construct, is relatively inexpensive and is effective for the purpose intended. By virtue of the symmetrical construction of the latch slide and the latch retainer, there is very little danger of binding occurring during use which would tend to prevent the normal operation of the latch and latch retainer. These parts may, if desired, be termed as being bi-laterally symmetrical about a plane of symmetry passing through the door pull, latch and latch retainer, along the line 2-2 shown in Fig. 1 of the drawings.

I claim:

1. A door locking mechanism comprising a housing,

means forming a latch slide within said housing, a latch positioned within said latch slide and adapted to slide along said latch slide from an open position to a closed position, first spring means located within said housing between said latch and housing so as to normally hold said latch in closed position, means forming a latch retainer slide within said housing, a latch retainer positioned so as to project into said latch retainer slide, said latch retainer adapted to slide along said latch retainer slide from a retracted position wherein said latch retainer is out of contact with said latch to an extended position wherein said latch retainer engages and prevents the movement of said latch to said closed position, second spring means located within said housing between part of said housing and said latch retainer, said second spring means serving to normally force said latch retainer toward said extended position, a control arm pivotally mounted within said housing, said control arm engaging said latch and adapted to slide said latch within said housing from said closed position to said open position against the pressure of said first spring means when said control arm is pivoted, a locking member rotatably mounted within said housing, said locking member having an opening therein for engagement with an actuating member, said locking member having cam means formed on the outer surface thereof, said cam means being adapted to engage said control arm to cause said control arm to pivot and move said latch from said closed to said open position, said cam means adapted to prevent the reverse pivotal movement of said control arm when engaged therewith and to permit such movement when not engaged therewith.

2. A door locking mechanism as defined in claim 1, said housing having a recess adjacent said latch retainer, said recess adapted to permit a hook to enter said housing and move said latch retainer from extended to retracted position, permitting said latch to move upwardly and engage said hook whenever said locking member and control arm are disengaged.

3. A door locking mechanism as defined in claim 1, including a locking retainer for said locking member movably mounted within said housing, and spring means located between said housing and said locking retainer so as to normally urge said locking retainer toward said locking member, said locking member having a non-round exterior surface, said non-round surface being adapted to engage a similar surface on said locking retainer to prevent undesired rotation of said locking member.

4. A door locking mechanism as defined in claim 1, wherein said latch, latch retainer and slides are bilaterally symmetrical about a plane of symmetry passing through said door pull, latch and latch retainer.

5. A door locking mechanism comprising a housing, a latch slidably located within said housing, first spring means located within said housing between said latch and said housing so as to normally move said latch toward closed position, a latch retainer slidably positioned within said housing, second spring means located within said housing normally urging said latch retainer into an extended position wherein said latch retainer is capable of limiting the movement of said latch toward said closed position, said latch retainer adapted to be moved from said extended position to permit movement of said latch to closed position, means located within said housing for moving said latch from said closed position back to a position where its movement is limited by said latch retainer, said means including an arm pivotally mounted within said housing, ball-shaped means formed on an extremity of said arm, and socket means formed within said latch engaging said ball-shaped means, said housing having an opening adjacent said latch retainer to permit the entry of a hook into said housing, said hook adapted to move said latch retainer from extended position against the pressure of said second spring means, said latch there-

upon adapted to be moved to closed position by said first spring means to engage said hook, said latch adapted to be disengaged from said hook by pivotal movement of said arm.

6. A door locking mechanism comprising a housing, means forming a latch slide within said housing, a latch positioned within said latch slide and adapted to slide along said latch slide from an open position to a closed position, spring means located within said housing between said latch and housing so as to normally hold said latch in closed position, a control arm pivotally mounted within said housing, said control arm engaging said latch and adapted to slide said latch within said housing from said closed position to said open position against the pressure of said spring means when said control arm is pivoted, and a locking member rotatably mounted within said housing, said locking member having cam means formed on the outer surface thereof, said cam means being adapted to engage said control arm to cause said control arm to pivot and move said latch from closed to open position, said cam means adapted to prevent the reverse

pivotal movement of said control arm when engaged therewith and to permit such movement when not in engagement therewith.

7. A door locking mechanism as defined in claim 6, including a locking retainer for said locking member movably mounted within said housing, and spring means located between said housing and said locking retainer so as to normally urge said locking retainer toward said locking member, said locking member having a non-round exterior surface, said non-round surface being adapted to engage a similar surface on said locking retainer to prevent undesired rotation of said locking member.
